MULTIPLE CIRCUIT BULB

Saviour Sammut, Jersey City, N. J.

Application April 10, 1935, Serial No. 15,523

3 Claims. (Cl. 176—27)

This invention relates to new and useful improvements in a multiple circuit bulb.

The invention has for an object the construction of a multiple circuit bulb which is characterized by an arrangement wherein a pair of filaments are associated with the device in a manner so that one filament is continuously used when the device is in a "live" socket, and the other auxiliary filament used as desired.

10 Still further the invention particularly proposes an arrangement whereby the auxiliary filament may be placed into and out of operation by the operation of a suitable switch.

15 Still further the invention also proposes an arrangement wherein the multiple circuit bulb is provided with an insulation member having a shell contact and an end contact for engagement in a conventional lamp socket and wherein the end contact has an inward directed extension 20 coactable with a movable contact to control the operation of the auxiliary filament.

25 Still further the invention proposes an arrangement whereby the movable contact is guided to move from a position in contact with said extension to a position out of contact for controlling the auxiliary filament.

30 Still further the invention also proposes an arrangement whereby the movable contact is snapped in either position as it is moved from one to the other position so as to maintain its condition of contact or its condition in which the contact is not made.

35 Still further the invention also proposes an arrangement whereby the movable contact may be latched in operative position so that both filaments operate in unison.

40 Still further the invention proposes the construction of a device as mentioned which is simple and durable and which may be manufactured and sold at a reasonable cost.

45 For further comprehension of the invention, and of the subjects and advantages thereof, reference will be had to the following description and accompanying drawing, and to the appended claims in which the various novel features of the invention are more particularly set forth.

In the accompanying drawing forming a material part of this disclosure:

50 Fig. 1 is a vertical sectional view of a multiple circuit bulb constructed according to this invention.

55 Fig. 2 is a fragmentary enlarged detailed view of a portion of Fig. 1 showing in particular the upper end.

Fig. 3 is a fragmentary sectional view taken on the line 3—3 of Fig. 1.

Fig. 4 is a horizontal sectional view taken on the line 4—4 of Fig. 1.

60 Fig. 5 is a fragmentary horizontal section view taken on the line 5—5 of Fig. 1.

Fig. 6 is a view similar to a portion of Fig. 2 but illustrating a modified arrangement.

Fig. 7 is a horizontal sectional view taken on the line 7—7 of Fig. 1.

The multiple circuit bulb according to this invention comprises a transparent vacuum casing 10 having an interior depending stem 11. This vacuum casing and stem preferably should be constructed of glass or similar non-inflammable material. An insulation member consisting of an 10 upper section 12 and a lower section 13 is attached upon the top of the casing 10 and is formed with an interior hollow region 14. This hollow region is arranged between the sections 12 and 13 15 so that when the sections are separated the hollow is exposed. In the normal operation of the bulb the sections 12 and 13 are permanently secured together such as with suitable cement or other arrangement.

20 A shell contact 15 is mounted upon the insulation member and is adapted to engage in a conventional lamp socket. An end contact 16 is mounted upon the end of the insulation member for engaging the end contact in a conventional lamp socket. This end contact comprises a ring 25 shaped member supporting an extension 16' extending into the hollow 14. A filament 17 is supported upon the lower end of the stem 11 on a plurality of supporting fingers 18 projecting from the stem. An upper auxiliary filament 19 is supported upon a plurality of members 20 supported upon the stem 11 at a higher point to the members 18.

25 The device is provided with a circuit by which the filament 17 is lighted when the bulb is engaged in a "live" lamp socket. This circuit extends from the end contact 16 to a lead 21 passing through the insulation member and through the depending stem 11 and directly attached upon one end of the filament 17. The other end of the 30 filament 17 connects with a lead 22 which also extends through the stem 11 and at the point 23 electrically connects with the shell contact 15.

35 A contact 24 is movably arranged in the hollow 14 and is adapted to engage with the extension 16' in one position and is also capable of assuming another position out of contact with the extension. More particularly the movable contact 24 slides upon a support bracket 25 which is attached to the under side of the insulation member 12. This bracket is formed at the free end with a head 26 limiting motion of the movable contact 24 to a position in which it engages with the extension 16'. The movable contact 24 is 40 capable of moving along the bracket to a position 45 out of contact with the extension.

45 A construction is arranged within the hollow 14 and is adapted to urge the movable contact into one or the other position. More particularly 50 this construction comprises a pair of rods 27 piv- 55

60

totally connected at the upper ends upon the sides of the movable member 24 and having their lower ends slidably engaging through openings in the top of a hollow member 28 mounted in the base 5 of the hollow 14. Expansion springs 29 are mounted upon the rods 27 and act against the pivots of the rods and the top of the casing 28. The openings in the top of the casing 28 through which the rods 27 extend are arranged upon the 10 dead center between the two extreme positions of the movable member. The arrangement is such that the springs 29 serve to hold the movable member in either position merely depending upon which position the movable member is in.

15 An arrangement is provided for manually moving the movable member from one to its other position. This means comprises cords 30 attached at one of their ends upon opposite ends of the movable member 24 and engaging through 20 supports 31 upon the sides of the hollow 14 and extending through passages 32 downwards to the extreme bottom end of the insulation member and to the exterior. Tags 33 and 34 are respectively attached upon the ends of the cords 30. 25 The tag 33 is provided with the word "on" designating that when this cord is pulled the movable contact 24 will be engaged with the extension 16'. The tag 34 is provided with the word "off" to indicate that this cord may be pulled to break the 30 connection.

35 A circuit is arranged in parallel with the previously mentioned circuit and is for the purpose of controlling the operation of the filament 19. This circuit extends from the shell contact 15 along the lead 22 to one end of the filament 19 through the filament 19 to a lead 35 which extends through the stem 11 to the hollow 14. At this point the lead 35 is formed with a curled portion 35' and then connects with the movable contact 24. The 40 object of the curled portion is to allow motion of the movable contact without disconnection of the lead 35 with the movable contact.

45 In Fig. 6 a modified form of the invention has been disclosed wherein the movable contact 24 is supported by a bracket 25' attached at its ends arranged upon the under side of the insulation member section 12. The movable contact 24 is slidably intermediate the ends of the bracket 25'. A set screw 36 threadedly engages through the 50 extension 16' from the exterior and is adapted to engage in an opening 24' in the movable member 24 for the purpose of holding the movable member in its operative condition. With this arrangement it is possible to lock the movable member in the operative condition so that the auxiliary filament will light simultaneously with the filament 17.

55 The operation of the device is as follows: The lamp may be engaged in a "live" lamp socket to 60 light the filament 17. A circuit exists from the end contact through the filament 17 to the shell contact. In the condition of the device illustrated in Fig. 1 of the drawing the auxiliary filament 19 will also light in that a circuit exists from the end contact 16, the extension 16', the movable contact 24, the lead 35, the filament 19, the lead 22 and the shell contact 15. If it is 65 desired to operate the lamp without the auxiliary filament 19 being lit, then the "off" cord 30 should be pulled so as to break the circuit of the auxiliary filament between the contacts 16' and 24. A feature of the construction is that the lamp 70 may be operated normally with one filament, may

be operated bright with both filaments, and may be operated with the auxiliary filament alone in the event that the normal filament burns out.

While I have shown and described the preferred embodiment of my invention, it is to be understood that I do not limit myself to the precise construction herein disclosed and the right is reserved to all changes and modifications coming within the scope of the invention as defined in the appended claims.

10 Having thus described my invention, what I claim as new, and desire to secure by United States Letters Patent is:—

1. A multiple circuit bulb, comprising a transparent vacuum casing with a depending interior stem, an insulation member attached on top of said casing and having a hollow region, a shell contact on said insulation member, an end contact on said insulation member and having an extension into said hollow, a pair of filaments on 15 said stem and within said casing, a circuit connecting in series the end contact, and one of said filaments, a contact slidably in said hollow region and engageable with said extension and movable to a position out of engagement with the extension, means for manually moving said contact from one to the other position, a circuit connecting in series said shell contact, the other filament, the movable contact and the end contact, and means for locking the movable contact 20 in engagement with said extension.

25 2. A multiple circuit bulb, comprising a transparent vacuum casing with a depending interior stem, an insulation member attached on top of said casing and having a hollow region, a shell contact on said insulation member, an end contact on said insulation member and having an extension into said hollow, a pair of filaments on 30 said stem and within said casing, a circuit connecting in series the end contact, and one of said filaments, a contact slidably in said hollow region and engageable with said extension and movable to a position out of engagement with the extension, means for manually moving said contact from one to the other position, a circuit connecting in series said shell contact, the other filament, the movable contact and the end contact, 35 means for locking the movable contact in engagement with said extension, comprising a screw 40 threadedly engaged through said extension from the exterior and engageable with said movable contact.

45 3. A multiple circuit bulb, comprising a transparent vacuum casing with a depending interior stem, an insulation member attached on top of 50 said casing and having a hollow region, a shell contact on said insulation member, an end contact on said insulation member and having an extension into said hollow, a pair of filaments on 55 said stem and within said casing, a circuit connecting in series the end contact, and one of said filaments, a contact slidably in said hollow region and engageable with said extension and movable to a position out of engagement with the extension, means for manually moving said contact from one to the other position, and a circuit connecting in series said shell contact, the other filament, the movable contact and the end contact, 60 comprising a screw threadedly engaged through said extension from the exterior and engageable with said movable contact, and engaging into an opening in the movable contact.

65 SAVIOUR SAMMUT.
